WALDEMAR THILMANY, OF CLEVELAND, OHIO.

Letters Patent No. 75,598, dated March 17, 1868.

IMPROVEMENT IN STEAM-ENGINE BALANCE-SLIDE VALVES.

The Schedule referred to in these Letters Patent and making part of the same.

TO ALL WHOM IT MAY CONCERN:

Be it known that I, WALDEMAR THILMANY, of Cleveland, in the county of Cuyahoga, and State of Ohio, have invented certain new and useful Improvements in Steam-Valves; and I do hereby declare that the following is a full and complete description of the construction and operation of the same, reference being had to the accompanying drawings, making a part of this specification, in which—

Figure 1 is a vertical transverse section.

Figure 2 is a transverse section.

Figure 3 is a top view.

Figures 4, 5, and 6 are detached sections, to which reference will be made.

Like letters of reference refer to like parts in the views.

My invention relates to the construction and arrangement of a steam-valve, so that the pressure of the steam exerted on the top of the valve is met by an equal pressure below, thereby neutralizing the first effective pressure of the steam on the valve, so that the said valve will work without pressure, hence with greatly reduced friction.

For a full and proper understanding of the construction of this valve, and its operation, a description of the same is as follows, viz :

In fig. 1, A represents a section of a steam-cylinder; B, the valve-seat; C C', the steam-throat; D, indicated by the circular dotted line, the eduction-pipe, shown also in fig. 3. E, the induction-port; F, the steam-chest; G, the face of the valve-seat; H H', the induction-ports leading to the throats C C', and J the steam-valve, all of which are or may be constructed in the ordinary way, with the exception of the valve, which will hereafter be further described.

The usual way, as is well known, of admitting steam to the cylinder, is through the eduction-pipe D into the chest F, thence into the cylinder through each port H H', respectively, and exhausting through the port E. In this manner of using steam a large pressure is exerted upon the valve, and being exerted on one side only, a great amount of friction is induced thereby, and a consequent rapid wearing of the valve and seat, hence a loss of power.

To avoid these results, steam is admitted under and into the valve to the cylinder, through the usual eduction or exhaust-port E, and made to escape through the usual eduction-port D, the reverse of the usual way. In order to accomplish this I construct a hollow open valve, as shown in fig. 6. This valve, like the ordinary one, is so made that it will cover both ports H H' at once, and thereby close the ports against the admission of steam, as shown in fig. 1. K is a cover, under which the valve slides, and, as it will be seen, extends either way shortly beyond the regular throw of the valve.

As above said, steam is admitted to the cylinder at the under side of the valve, instead of the top, in the ordinary way. Thus, from the exhaust E, through the port I, into the valve, which on being moved from the position shown in fig. 1, to that shown in fig. 4, in which it will be seen that the induction-port H is partially open before the port H', so that the steam may begin to exhaust just before taking steam through port H', which it will do on being moved to the position shown in fig. 5, the steam passing in the direction of the arrows, and at the same time exhausting through port H, around the ends and above the cover K, into the steam-chest F, from which it escapes through the usual induction (as used in the ordinary way) pipe D, to the exhaust connected thereto; and so on the reverse movement of the valve by the eccentric, a reverse direction will be given to the steam, thus exhausting through H' into the chest, and taking steam through H, and so on alternately, as the piston traverses the cylinder, taking steam through the valve, and exhausting it on the outside of the same. The valve being made hollow, it will be obvious that on the admission of steam the pressure will be exerted equally upon it upward and downward, therefore the pressure being changed from one side of the valve, and made to press alike in opposite directions, the pressure is lost by mutual reaction; hence the valve will work free of pressure of any considerable amount. But as the valve is an open one, and the opening covered by the plate K, the said plate is thereby exposed to the direct pressure of the steam from below, and hence would be forced upward out of place, away from the valve, if not restrained by a corresponding pressure from above. To produce this corresponding pressure, a pair of disks or pistons, A', fig. 1, is arranged upon the

top of the cover K. These disks or pistons are fitted in a ring or collar, B', fig. 2. C' are followers fitted to each end of the ring, and secured to the same by screws a, the ring and followers forming a kind of stuffing-box, in which the pistons work steam-tight.

It will be seen that the two pistons do not touch each other, there being a short space, b, between them, and preserved by the lugs c, which prevent the two disks from touching. The upper end of the upper disk or piston rests against the under side of the chest-cover L, whereas the lower end of the bottom piston rests upon the valve-cover K. Now, it will be evident that on admitting steam into the space b, between the pistons, the result will be to force them away from each other, and if the area of the face of each of the pistons is equal to the area of the opening in the valve, it will be obvious that the pressure of steam exerted on the bottom piston will be equal to that on the space of the cover K, over the opening in the valve; hence the pressure being equal on both sides of the plate K, it will remain in place. Steam is admitted between the pistons through the holes d d', thus taking steam directly from the valve at full pressure. As the face of the valve and seat may wear away, the pistons will be forced further from each other, and thereby keep the plate K at all times close and steam-tight down upon the valve. When the valve is in the position shown in fig. 1, or passing from that to the position shown in figs. 4 and 5, the pressure of the steam on the valve in consequence of the walls of the ports, will be greatest when the valve is full over the ports; hence the pressure would be unequal. In order to meet this extra pressure, steam is admitted above the valve into the spaces J', immediately over the ports, and which are of the same area as the ports therefor, the steam acting in opposite directions neutralize each other; hence the valve is relieved from the pressure alluded to.

What I claim as my improvement, and desire to secure by Letters Patent, is—

1. The arrangement of the valve J, plate K, lugs c, and passages d d', with reference to the cylinder A, substantially as specified.
2. The pistons A', as constructed and arranged in relation to the plate K, substantially as set forth.

WALDEMAR THILMANY.
